CLAIM

The ornamental design for a catheter package, as shown and described.

DESCRIPTION

FIG. 1 is a front perspective view of a catheter package, showing the new design;

FIG. 2 is a rear elevational view thereof. The front elevational view being a mirror image thereof;

FIG. 3 is a right side elevational view thereof;

FIG. 4 is left side elevational view thereof;

FIG. 5 is a top plan view thereof;

FIG. 6 is a bottom plan view thereof;

FIG. 7 is a front perspective view of a second embodiment of a catheter package, showing the new design;

FIG. 8 is a rear elevational view thereof. The front elevational view being a mirror image thereof;

FIG. 9 is a right side elevational view thereof;

FIG. 10 is left side elevational view thereof;

FIG. 11 is a top plan view thereof; and,

FIG. 12 is a bottom plan view thereof.

The broken line showing of a circle in FIGS. 1-2 and FIGS. 7-8 is included for the purpose of illustrating environmental structure and forms no part of the claimed design.
